TOY TUBE TESTING DEVICE

Charles Pearson, Jr., 396 Huntington Lane, Elmhurst, Ill.

Filed May 19, 1959, Ser. No. 814,260

5 Claims. (Cl. 46—39)

This invention relates to a toy tube testing device.

One of the objects of this invention is to provide a toy indicator for indicating whether a simulated television tube or the like is operative or inoperative.

Another object of this invention is to provide a toy testing device which is used to simulate the testing of television tubes for the purpose of indicating whether the simulated television tube will be operative when inserted in a simulated television receiving set.

I have filed a companion application Serial No. 814,259 on a battery operated toy which simulates a television receiving set, which is provided with a plurality of sockets connected in series to a light bulb positioned inside a simulated picture tube. By selecting the proper tubes and inserting the same in the sockets the circuit is closed so that the light bulb is illuminated. The toy testing device of the present invention is for use with such a toy in that this testing device will indicate whether the tube will close the circuit.

More specifically, the simulated tubes all appear to be substantially the same, however, the difference is in the length of the pin prongs, which difference is not discernable to the child. Tubes having the slightly longer pin prongs will operate to close the circuit in the toy television receiving set, while those having shorter pin prongs will leave the circuit open, thus, those tubes with the longer pin prongs are considered "good" tubes and those with the shorter pin prongs are considered "bad" tubes. This invention enables the child to select the proper tubes.

Other objects will become apparent as this description progresses.

In the drawings:

Figure 1 is a top view of this invention.

Figure 2 is a view from the bottom or underside.

Figure 3 is a view partly in cross-section taken on lines 3—3 of Figure 1 with a tube inserted for testing.

Figure 4 is a view of the two types of simulated tubes to be tested and showing particularly the differences in the length of the pin prongs of the tubes, and

Figure 5 is a view showing the means for releasably securing the pointer.

The toy television tube tester comprises a housing generally indicated at 10 which may be integrally molded of plastic or like material. The housing has a substantially flat surface 12 and a raised rectangular shaped frame-like upper portion 14. A flat surface 16 is provided below the frame 14 and the upper portion of said surface is marked with any suitable indicating or measuring indicia used in testing conventional television tubes. For purposes of illustration the word "Good" is positioned adjacent the center line 18 and the word "Bad" is positioned to the right thereof, as best shown in Figure 1. These two designations are intended to indicate when a tube tested is either good or bad for the purpose for which same are intended.

Rotatably supported on the flat surface 12 of the housing is a knurled knob 20 having a stem portion 22 extending through a small opening in the flat surface 12. Fixed

2

ly secured to the stem portion 22 is a pointer generally indicated at 24. The upper end of the pointer extends through an elongated slot 26 in the bottom wall of the frame to permit movement of the pointer. The pointer extends to the indicating scale previously described. The lower portion of the pointer 24 is stepped down as indicated at 24' to provide a defined spacing or clearance between it and the flat surface 12 of the housing. The surface 12 is provided with a plurality of spaced openings 28 arranged in a circle to receive the pin prongs of the tubes to be tested.

The openings 28 are to the left of the pivotal axis of the pointer 24 and in the path of the sweep of the lower portion 24' of the pointer, for the purpose to be described. A coil spring 30 having one end attached to the pointer as at 32 and the other end to a stud 34 which is secured to the housing 10 normally biases the pointer 24 so that when released it sweeps to the dotted line position shown in Figure 1 and is stopped by another stud 36 secured to the housing.

To set the pointer for operation, the knurled knob 20 is manually engaged by the fingers of a hand and the pointer 24 is rotated to the left, as shown in full lines in Figure 1, against the tension of the spring 30. Means 25 are provided to releasably hold the pointer 24 in this position until the tube to be tested is inserted in the openings 28. Said means are best shown in Figures 2, 3 and 5 and comprise an L-shaped metal spring member 38 secured as at 40 to the housing 10.

The forwardly extending portion of said member 38 is positioned to extend below the lower end of the pointer portion 24' and is provided with an indentation 38' to receive a rib 42 formed on the underside of the lower end of the pointer. When the pointer 24 is rotated so that it engages the member 38, it will lock itself thereto by the engagement of the rib 42 with the indentation 38'. To release the pointer a plunger generally indicated at 44 is provided. The plunger has a stem 46 vertically slideable in the sleeve 48 supported on the underside of the housing 10.

A cap 50 is secured to the top of the stem 46 of the plunger and a spring 52 is enclosed within the cap to normally maintain the plunger in its elevated position out of engagement with the spring member 38. By depressing 45 the plunger the spring member 38 is depressed, releasing the pointer 24 to swing to the right, provided it clears the pin prongs of the simulated tube to be tested.

In Figure 4 there is shown two types of simulated tubes to be tested. The only difference between the two is in the length of the pin prongs. All tubes have six spaced pin prongs extending from the bottom to be received in the spaced openings 28. The pin prongs 54 in tube G (for Good) are longer than the pin prongs 56 in tube B (for Bad). When tube G is inserted in the openings 28 and the pointer 24 is released by depressing the plunger 44, the movement of the pointer will be arrested when it makes a half sweep, due to engagement of the lower end 24' of the pointer with some of the pin prongs 54 of the tube G. This positions the top of the pointer adjacent line 18 to indicate Good on the scale, meaning that this tube when used is in operating condition. When the tube B is inserted in the openings 28 and the pointer is released, the pointer will complete its sweep to that indicated in dotted lines in Figure 1, for the reason that the short pin prongs 56 will not be engaged by the lower end 24' of the pointer.

While the tester is shown in connection with simulated television tubes, it will be understood that it may be used with other types of simulated tubes, such as simulated radio tubes and the like.

This toy provides a source of play value in testing

simulated tubes for use in a companion simulated television receiving set.

It will be understood that various changes and modifications may be made from the foregoing without departing from the spirit and scope of the appended claims.

I claim:

1. A toy testing device for testing simulated television tubes and the like, certain of said simulated tubes having long pin prongs and other of said simulated tubes having short pin prongs, said device comprising a housing, a tube socket in said housing, said socket having a plurality of openings to receive the pin prongs of the simulated tube, an indicator lever rotatably secured to the housing, said lever passing under said openings when rotated, at least one of the pin prongs of said long pin prong tube extending in the path of movement of said indicator lever to stop same at a certain predetermined point.

2. A toy testing device for testing simulated television tubes and the like, certain of said simulated tubes having long pin prongs and other of said simulated tubes having short pin prongs, said device comprising a base, a tube socket in said base, said socket having a plurality of openings to receive the pin prongs of the simulated tube, an indicator lever rotatably secured to the base to rotate with respect to said base, said lever having a portion thereof extending below the base and in line with the openings in said socket to pass under said openings when rotated, said long pin prongs extending through said openings and in the path of movement of said indicator lever to thereby stop same at a certain predetermined point.

3. A toy testing device for testing simulated television tubes and the like, certain of said simulated tubes having long pin prongs and other of said simulated tubes having short pin prongs, said device comprising a base, a tube socket in said base, said socket having a plurality of openings to receive the pin prongs of the simulated tube, an indicator pointer pivotally secured to said base to rotate with respect to said base, said pointer having a portion extending below said socket receiving openings to pass under said openings during movement of said pointer to be en-

gaged by the pin prongs on said long pin prong tube to thereby limit the movement of said indicator pointer at a certain predetermined point.

4. A toy testing device for testing simulated television tubes and the like, certain of said simulated tubes having long pin prongs and other of said simulated tubes having short pin prongs, said device comprising a base, a tube socket in said base, said socket having a plurality of openings to receive the pin prongs of a simulated tube, an indicator pointer pivotally secured to said base to rotate with respect to said base, said pointer having a portion thereof extending below said openings to pass under said openings during movement of said pointer to be engaged by said long pin prongs to limit the movement of said indicator pointer at a certain predetermined point, means for normally urging said indicator pointer in one direction, releasable means for holding said indicator pointer in an opposite direction, said indicator pointer when released adapted to move in the direction of said first mentioned direction unless stopped by the long pin prongs of the tube.

5. A toy testing device for testing simulated television tubes and the like, certain of said simulated tubes having long pin prongs and other of said simulated tubes having short pin prongs, said device comprising a base, a tube socket in said base, said socket having a plurality of openings to receive the pin prongs of the simulated tube, a pointer pivotally secured to said base to rotate with respect to said base, said pointer having a portion passing under said socket openings during movement of said pointer to be engaged by said long pin prongs of said tube to arrest travel of said pointer, means for manually setting said pointer in starting position before insertion of a tube in said socket, and means for releasing said pointer to permit said pointer to move in the opposite direction.
